UNITED STATES PATENT OFFICE.

ADELARD FRANCIS MARTEL, OF MONTREAL, QUEBEC, CANADA, ASSIGNOR, BY MESNE ASSIGNMENTS, TO THE HAND POWER TEST MACHINE COMPANY, OF NEW JERSEY.

COIN-CONTROLLED HAND-POWER TESTER.

SPECIFICATION forming part of Letters Patent No. 394,193, dated December 11, 1888.

Application filed May 8, 1886. Serial No. 201,595. (No model.)

To all whom it may concern:

Be it known that I, ADELARD FRANCIS MARTEL, of Montreal, in the county of Hochelaga and Dominion of Canada, have invented certain new and useful Improvements in Hand-Power Testers, of which the following is a specification.

My invention relates to a machine for testing the muscular strength of the hand and arm; and it consists in a novel construction and operation of the same, as hereinafter fully described and claimed.

In the drawings, Figure 1 is a perspective view of my improved tester; Fig. 2, a face view; Fig. 3, a detail view.

A indicates a box or framing, and B a handle rigidly secured to one of the outer faces thereof. The box A is further provided on one face with a glass dial, C, and on its interior with a receptacle or drawer, D, which opens on the rear of the box.

E represents a skeleton frame secured to the sides of the box and extending across the same, as shown in all the figures, the frame comprising three vertical bars, *a b c*, and two substantially horizontal bars, *d* and *e*.

Projecting out through the side of the box and passing loosely through the bars *b* and *c* is a rod or bar, F, which at its outer end is fashioned into a handle, *f*, which is preferably in the same vertical plane with handle B. Where the rod F passes through the bar or support *b* it is preferably made cylindrical, and beyond said support *b* the rod is encircled by a strong spiral spring, *g*, the latter being prevented from escaping from the rod F by means of a collar, *h*, rigidly secured to the rod, as shown in Figs. 2 and 3. It will thus be seen that the spring *g*, bearing at one end against the bar or support *b* and at the other end against the collar *h*, serves to hold the bar or rod F in the box, and in order to draw said bar or rod outwardly the force of the spring must be overcome.

To one side of the rod F, in advance of the barb *b*, is secured a rack-bar, G, which engages with a pinion, H, journaled in a bracket, *i*, formed upon the frame E. The rack-bar extends beyond the pinion H, parallel with the rod F, and has its end turned upward and

provided with a plate or guard, *j*, for a purpose presently explained.

The pinion H is rigidly secured to a shaft, *k*, which latter is extended outward toward the dial-plate C and provided with a finger or pointer, *l*, the shaft *k* being opposite the center of the dial. Now, of course, as the rod or bar F is pulled out of the box and the spring *g* thereby compressed, the rack-bar G, which is rigidly secured to the rod or bar, will move with the latter and turn or rotate the pinion H and the pointer *l*. The pointer *l*, in thus turning with its shaft, will move over the dial C, and thus the force exerted will be indicated by the finger on the dial.

In order to prevent the device from being operated without compensation, I provide a catch or retaining device which is released by the deposit of a coin of a predetermined weight or value.

J indicates a beam or lever pivoted between its ends in lugs *l*, formed upon the frame E, and carrying at one end a small box or receptacle, *m*, and at its other end a pendent dog or bar, *n*, as shown in Figs. 1, 2, and 3. The lever J is further provided with a weight, *o*, which is adjustable upon the lever in order to balance the same and vary the action thereof. The dog or bar *n* is made in the form of a yoke to give the necessary weight and engages in a notch, *p*, in the sliding bar or rod F, as shown. When the dog *n* is in the notch *p*, as shown in Figs. 1 and 2, it will be seen that it is impossible to pull the rod F outward, as the dog rests against the upright *c* on one side and against one of the upright walls of the notch *p* on the other side. When, however, a coin is dropped into the box or receptacle *m*, the weight of the former causes the longer arm of the lever J to descend and thereby raise the dog *n* out of the notch and allow the rod F to be pulled outward.

By adjusting the weight *o* upon the lever J the latter may be adjusted so as to tip and release the rod F when a five-cent piece is dropped into the receptacle *m*, or so that it will be necessary to insert a quarter or a half dollar piece, or any other coin, as may be desired.

As the lever J, with its receptacle or box *m* 100

and the contained coin, descends it moves closely to the guard *j*, and when the lower edge of said guard *j* is reached the coin rolls out through the side of the box *m* below the lower edge of the guard and into a funnel-shaped tube, *K*, which communicates at its lower end with the drawer *D*, the guard preventing the escape of the coin until the lever *J* reaches its proper position.

To insure the proper insertion of the coin, I employ a feeding-tube, *L*, which is open on the exterior of the box *A* and terminates at its inner end directly over the box or receptacle *m*.

In order to cause the dog *n*, which is pivoted at its upper end to the lever *J*, to rise and fall in a straight line, I provide the framing *E* with arm or finger *q*, which may bear against one face of the dog and prevent its swinging out of line. It is obvious that a flat coiled spring may be substituted for the spiral spring shown, or that a system of levers and weights may be substituted for the spring, these being the mechanical equivalents of one another.

In using the device for testing the strength of the hand, the handle *B* is grasped in the palm of the hand and the fingers are passed around the handle *f* of the rod *F*.

In order to limit the inward movement of the rod *F*, the latter is provided with a stop or collar, *r*, which strikes against the outer face of the box and limits the movement of the bar.

Having thus described my invention, what I claim is—

1. In a device for testing muscular strength, the combination, with a graduated dial and with handles to be grasped by the operator, of a catch and a coin-receiver arranged so that when a coin is placed within the receiver it shall release the catch and permit the device to be operated and the power or strength to be indicated upon the dial.

2. In an apparatus for testing muscular strength, the combination of a registering device, handles to be grasped by the hand, a locking device to prevent the actuation of the registering device, and a coin-receiver adapted and arranged to act upon and release the locking device, and thus to permit the registering device to be actuated when a proper coin is placed in the coin-receiver.

ADELARD FRANCIS MARTEL.
